MANUFACTURE OF THREAD OR THE LIKE

Charles E. Herrstrom, Lakewood, Fred J. Samerdyke, Rocky River, and Walter S. Barlow, Lakewood, Ohio, assignors to Industrial Rayon Corporation, Cleveland, Ohio, a corporation of Delaware

Application October 6, 1938, Serial No. 233,608

5 Claims. (Cl. 18—54)

This invention relates to methods of processing and packaging thread or the like, particularly artificial silk thread. As hereinafter used, the term "thread" is employed to cover thread-like articles generally; i. e., filaments, threads, tapes, ribbons, foils, etc., whether of natural or synthetic origin. As applied to the manufacture of thread of synthetic origin, the invention may be employed to equal advantage with thread produced according to pot-spinning, spool-spinning, and continuous processing systems, wholly without regard to whether the thread has been manufactured according to the viscose, cellulose acetate, cuprammonium cellulose or casein process. For the sake of convenience, the invention will be described hereinafter as applied to the production of multiple filament viscose artificial silk thread.

In the pot- and spool-spinning systems of manufacturing multiple filament viscose artificial silk thread, the thread is extruded from a spinneret, coagulated by conventional methods, and collected in a rotating pot in the pot-spinning system or wound with the aid of a reciprocating guide upon a spool in the spool-spinning system. According to usual practice, the pot-spun cake or spool package is subjected to further processing treatment, either in the original package or in skeins into which the thread is wound on skein reeling machines. In either case, many disadvantages reside in the long sequence of operations incident to the processing of the thread and its subsequent collection in the form of a precision-wound cone package, among which is the necessity of repeatedly handling the wet thread, with consequent likelihood of damage, at a time when its tensile strength is comparatively low.

In the manufacture of continuously processed thread, most of the processing steps; i. e., desulphurizing, bleaching, etc., are performed in sequence immediately following the coagulation of the thread. However, because of limitations of space, it is not ordinarily possible to include in the sequence certain treatments which it may be desired to perform upon the thread; for example, dyeing, sizing, and other processing operations intended to be followed by collection in the form of a precision-wound cone package. The method of the present invention has the advantage that, in addition to being adapted to the after-treatment of pot- or spool-spun thread, it is equally useful in the case of continuously processed thread such, for example, as that produced by the process and apparatus of Knebusch et al. Patent 2,225,642.

Among other things, the present invention contemplates the processing of the thread by an improved method pursuant to which thread from a suitable supply source is advanced in helical form upon the periphery of at least one thread-advancing thread store device on which it is subjected to any desired processing treatment or treatments. One of the objects of the invention is to provide a method of processing, drying, and precision-winding thread, which method is simple in operation, dispenses with certain of the steps heretofore necessary, and eliminates costly manual operations. Still another object is to produce in self-sustaining package form a thread with an extremely high degree of uniformity in its physical and physico-chemical properties. Further objects of the invention will appear more in detail hereinafter.

In the accompanying drawings, in which corresponding parts bear corresponding reference characters, Figure 1 represents a front elevation of apparatus for after-treating thread originally collected in untwisted condition upon a spin spool, such apparatus comprising twisting means, a plurality of thread-advancing thread store devices, and a coning device for forming the thread into a precision-wound cone package. Figure 2 is a sectional elevation along line 2—2 of Figure 1. Figure 3 is a rear elevation of the apparatus of Figure 2. Figure 4 is a front elevation of an apparatus generally similar to that of Figure 1 which is adapted to withdraw the thread from the spin spool package, process the untwisted thread, and form it into a precision-wound cone package. Figure 5 is a sectional elevation along the line 5—5 of Figure 4.

Figure 6 represents a partial sectional elevation similar to Figure 5 of apparatus for the processing, drying and coning of thread produced by the pot-spinning system. Figure 7 is a front elevation of apparatus for processing, drying and coning pretwisted thread originally collected upon a cap twister bobbin. Figure 8 is a sectional elevation along the line 8—8 of Figure 7. Figure 9 is an enlarged sectional elevation of one form of thread-advancing thread store device particularly well adapted to the practice of the invention; viz., a thread-advancing reel of cantilever form. Figure 10 is an end elevation of the reel of Figure 9. Figure 11 is an end elevation of one form of apparatus adapted to produce the thread, completely process it, and collect it in precision-wound package form.

In the apparatus illustrated in Figures 1 and 2, which is adapted to the twisting, processing and

coning of thread originally collected in a spool-spun package, the thread 11 is withdrawn from the package formed upon a spool 12 and passed through the guides 13 and 14 to the first of a plurality of reels 15, 16, 17, 18, and 19. A predetermined amount of twist is introduced in the thread 11 as it is withdrawn from the spool 12 by reason of the fact that said spool is rotatably mounted upon the twister apparatus 21 so that thread 11 is caused to be unwound at a rate greater than the rate of take-up of said thread upon the first reel 15. As the thread traverses the periphery of each of the reels 15, 16, 17, and 18, it is subjected to one or more processing treatments after which it is dried upon the tapered drying reel 19 and passes to the coning device 22 to be collected in the form of a precision-wound cone package 23.

The reels 15, 16, 17, 18, and 19 are preferably of the type illustrated in Figures 9 and 10. Reels of this type are advantageously employed in the apparatus of the present invention because their construction is such as to permit of their being supported from one end only thereof, leaving their other ends unsupported and unobstructed by anything impeding the discharge of the thread. In addition to the fact that all of the unsupported ends of the reels are presented to a common front, the reels are arranged in what may be termed vertically stepped relation in a manner such that the thread-receiving portion of each reel other than the first is directly below the thread-discharge portion of the preceding reel.

The typical reel illustrated in Figures 9 and 10 is generally of the type shown, described and claimed in Knebusch Patent 2,210,914. The reel comprises two rigid, generally cylindrical members 24 and 25, of which member 24, which is referred to as the concentric member, is mounted concentrically upon and for rotation with drive shaft 26. Member 25, which is known as the eccentric member, is rotatably mounted with its axis slightly offset from and inclined to that of the concentric member 24. The periphery of the concentric member 24 includes a plurality of longitudinally extending bar members 27 which alternate with an equal number of similar bar members 28 forming the periphery of the eccentric member 25.

Concentric member 24 may comprise a cylindrical body portion 29 which serves to support and lend rigidity to bar members 27. Although there are various means for mounting said concentric member, a cap nut 31 may be employed to hold said member 24 against a suitable shoulder on drive shaft 26. Said concentric member 24 may be made to rotate with the shaft 26 by means of a pin 32 inserted through said shaft and seating in a slot 33 in the hub of the concentric member 24. Thus concentric member 24 consists essentially of a rigid cage member fixedly mounted upon shaft 26.

Eccentric reel member 25 may conveniently take the form of a rigid cage member, being preferably made up of bar members 28 provided at their outer ends with an internal annular reinforcing ring 34 and at their inner or driving ends with an external annular reinforcing ring 35 by means of which the eccentric member 25 is concentrically mounted upon an annular supporting member 36. Said annular supporting member 36 is rotatably mounted upon frame member 37 with its axis in spaced and inclined relation to the axis of concentric member 24.

Drive shaft 26 may as shown be journalled in the frame member 37. A flexible sealing means 38 may be provided for the purpose of preventing corrosive processing liquids from attacking the bearings and other metal surfaces.

When the drive shaft 26 is rotated, concentric member 24 fixed thereto rotates therewith. Eccentric reel member 25 is rotated by contact between the bar members 27 and 28 of concentric member 24 and eccentric member 25, respectively. As the reel rotates, the offset relation of the bar members 27 and 28 causes the thread to be supported first by the bar members of one of the cage members and then by the bar members of the other. The inclined relation between the two cage members causes the thread to advance longitudinally of the reel from the supported to the unsupported end thereof in a large number of closely spaced, generally helical turns.

All of the reels shown in the apparatus of the various illustrated embodiments of the invention operate in the same manner and are of the same general type as that disclosed in Figures 9 and 10. Preferably they are mounted in the manner shown in Figure 2 with their axes extending very nearly horizontally; i. e., substantially perpendicularly to a vertical plane parallel to the operating face of the machine. However, in the apparatus of Figures 1 to 8, inclusive, the reels are not, strictly speaking, horizontally mounted, since they are tilted upward at a slight angle to obtain countercurrent flow of the respective processing liquids, as will be explained in detail hereinafter.

Since the reels of Figures 9 and 10 are of cantilever form, they may be supported at one end only, leaving the other end free from any obstruction, thus making it a relatively simple matter to thread up or start the thread upon each reel. As indicated in Figure 2, the thread first comes into contact with reel 15 at its supported end and progresses in the manner previously explained toward the unsupported end thereof, at which end it is discharged from said reel. The thread comes into contact with the thread-receiving portion of the next reel 16 at the supported end thereof, as also upon all subsequent reels. It is obvious that various other dispositions of the reels with respect to each other, including variations of vertical and horizontal arrangements, may be employed, if desired, together with a larger or smaller number of reels than here shown.

The illustrated embodiment of the present invention contemplates a plurality of thread-processing units which may be disposed longitudinally of the machine. As shown in the embodiment illustrated in Figure 2, each such unit comprises an appropriate thread supply source; a plurality of reels such, for example, as reels 15 to 19, inclusive; a suitable apparatus such as the coning device 22 for forming a precision-wound package; and, if desired, means such as the twister apparatus 21 for twisting an untwisted thread or for introducing additional twist into a previously twisted thread. Apparatus including a plurality of such thread-processing units is illustrated in Figures 1, 2 and 3.

Such a machine comprises two vertical frame members 39 and 41 which serve to support the longitudinally extending frame members 42 and 43 to which are secured the inclined members 44. Cross member 45 and longitudinal members 46 support a plurality of twisters 21. The twister apparatus includes a gear box 47 which through

suitable gearing actuated by the shaft 48 extending lengthwise of the machine operated from a power source (not shown) drives the spindle 49 on which the spool 12 or other form of collection package is secured by means of the cap 51. A clutch mechanism operated by the lever 52 permits the disengagement of the gears contained in the gear box driving the spindle 49 to permit the replacement of empty spools with filled ones.

To the inclined members 44 are secured the processing reels 15, 16, 17, and 18 and the drying reel 19. Associated with the liquid processing reels 15 to 18, inclusive, are troughs 53 which extend lengthwise of the machine and serve a plurality of reels on the same horizontal level. The troughs 53 are so constructed as to incorporate therein a supply conduit 54 and drain channel 55. The appropriate processing liquid is carried in said supply conduit 54 and is showered upon the reels at points nearest the free ends thereof by means of distributors 56.

As previously explained, the free ends of said reels are tilted slightly above the supported ends and thus cause a countercurrent flow of liquid reagents from the unsupported end of the reel toward the supported end. The liquid reagent drips off the reels, is caught in the drain channel 55 of the trough 53, and is carried away by means of a suitable piping arrangement (not shown) to the sewer in the event that it is impracticable to re-use the liquor or, alternatively, to suitable make-up means. Since it has been found desirable to re-use certain of the reagents, suitable pumps and piping arrangements (not shown) may be provided to recirculate the same back to the proper supply conduits 54.

The processing reels 15, 16, 17, and 18 and drying reel 19 are driven by the inclined shafts 57 through the gearing 58. The shaft 59 extending 40 lengthwise of the machine rotated by a power source (not shown) actuates a plurality of inclined shafts 57 through gearing 61. The inclined shafts and gearing are fully enclosed by housings 62 shown in Figures 2 and 3 which serve to protect the thread 11 and prevent the leakage of lubricant. Although the thread 11 may be dried by any suitable means, drying is preferably accomplished upon the tapered drying reel 19. Electricity, live steam, hot air or hot water may be employed to heat the reel elements. In the apparatus of the present invention, hot water is used as the heating medium and longitudinally extending conduits 63 and 64 serve to supply and to remove the hot water from all of the drying reels 19. Each reel 19 is enclosed by a housing 65 provided with a door 66 to facilitate inspection and manipulation of the thread.

Thread 11 passes from the processing reels 15 to 18, inclusive, to the drying reel 19 and thence through a suitable tensioning device 67 and guide 68 to apparatus for the forming of a precision-wound cone package capable of immediate commercial use in knitting and weaving operations. It is desirable that the apparatus be adapted to take up the thread at a substantially constant linear speed and form therefrom a self-sustaining package of suitable form. One type of coning device adapted to accomplish this is illustrated in the accompanying drawings, in which it is designated generally by reference character 22.

Each coning device 22, of which one is provided for each descending series of reels, is mounted upon the longitudinal beams 71 supported by the frame member 39. It comprises a package sup-

port 72, a friction roller 73, a traverse guide 74 operated by cam 75, and a form of clutch mechanism manually controlled by a lever 76. A paper cone is placed upon the support 72 which is mounted in such manner as to permit free pivotal movement. The support 72 permits the cone and the package 23 to rest upon the friction roller 73 which is fixedly mounted upon and driven by shaft 78 carrying a plurality of said rollers 10 and rotated by a suitable power source (not shown). Thread 11 is formed into a precision-wound cone package by the traverse guide 74, which is reciprocated lengthwise of the package. Cams 75 are mounted upon shaft 79, which is actuated by a suitable power source (not shown).

A conventional combination of springs and levers incorporated in the coning device and operated by the guide 68 cooperates with the package support to move the package automatically 20 out of driving contact with the friction roller 73 in the event of thread breakage. The device may be manually disengaged for the purpose of removing a completed package by the manipulation of the clutch lever 76. The device, if automatically tripped, may be reset by operating the clutch lever 76. This mechanism makes possible the operation of a plurality of such coning devices from one power source and obviates the necessity of shutting down the entire machine in 30 the event of breakage of but a single thread.

The apparatus of Figures 1, 2 and 3 is adapted to operate upon any form of thread, twisted or untwisted; to introduce a twist into said thread; to subject it as desired to a plurality of processing treatments which may include desulphurizing, bleaching, washing, sizing, dyeing, oiling, drying, etc.; and to collect it in a precision-wound frusto-conical package. The machine illustrated in Figures 4 and 5 is generally similar to that of Figures 1, 2, and 3. It is adapted to subject to similar liquid processing treatments, to dry, and to cone an untwisted thread produced according to the conventional spool-spinning process.

With a view to its use in certain types of fabrics in which an untwisted thread may be employed to advantage, the untwisted thread 11a (Figures 4 and 5) may be unwound directly from the spin spool, subjected to processing treatment, and coned. To that end, the twister apparatus 21 of the machine of Figure 2 is entirely eliminated in the apparatus of Figures 4 and 5. Thread 11a is withdrawn from the spin spool 81 mounted upon a channel 82 extending lengthwise of the machine and supported from the machine frame members 39 by end brackets 83. Guides 84 and 85 serve to direct the thread to the thread-receiving end of the uppermost reel 15 in a processing series including reels 15 to 18, inclusive. Thread 11a is subjected to any desired treatment or treatments as it progresses along each of the reels in the series, after which it is dried upon a tapered drying reel 19 and collected in a precision-wound cone package by the coning device 22.

The embodiment of the invention as illustrated in Figure 6 is substantially similar to that of Figures 4 and 5 with the exception that the thread 11b is withdrawn from a pot-spun cake 86 produced according to the conventional pot-spinning process. Channel 87 extending lengthwise of the machine supported from the machine frame by the transverse beam 88 and angles 89 serves to carry a plurality of thread packages 86. Since the pot-spun thread 11b is pretwisted,

twisting apparatus of the type disclosed in the embodiment of the invention illustrated in Figures 1 to 3, inclusive, may be omitted unless, of course, it is desired to produce a highly twisted or crepe thread.

In Figures 7 and 8 is illustrated a machine differing from that of Figures 4 and 5 only in that it is adapted to process, dry and cone a twisted thread 11c such as that produced according to a continuous process upon apparatus of the type shown, described and claimed in the aforementioned Patent 2,225,642. Thread 11c is unwound from the cap-twister bobbin 91 upon which it is collected after being processed, dried and twisted upon a continuous processing machine in the manner described in detail in the foregoing application.

A plurality of thread packages 91 are supported in an inclined position, as shown in Figure 8, by spindles 92 secured to the longitudinally extending member 93. The member 93 is supported from the frame of the machine by the beam 94 at either end of said machine. The apparatus of Figures 7 and 8 may, if desired, as indicated in the description of the other embodiments of the invention, be equipped with a twister device such as that illustrated in Figure 2 to uptwist the pretwisted thread 11c.

Numerous other modifications may be made without in any way departing from the scope or spirit of the invention.

For example, in adapting the method of the present invention to the production and treatment of artificial silk it is readily possible to add a spinning means such as a spin bath, spinnerets and associated auxiliary thread producing apparatus to the upper end of the machine, so that the thread may be produced, processed, dried and coned all upon one machine. Such a machine may conveniently take the form of the modified continuous processing apparatus of the kind described in detail in Patent 2,225,642 hereinbefore referred to. Such a machine is illustrated in Figure 11 of the accompanying drawings.

The multiple filament thread 11d is extruded from the spinneret 95 into a suitable spin bath contained in the longitudinally extending trough 96. Thread 11d is directed by suitable guides to the reel 97 from which it passes in succession to the reels 98 to 106, inclusive, generally of the type hereinbefore described (Figures 9 and 10) and thence to the coning device 107. The aforementioned reels may be arranged in any suitable fashion. For convenience they are arranged here in a manner similar to that shown in the embodiments of Figures 1 and 2, previously described in detail. Upon each of the reels 98 to 106, inclusive, one or more processing steps may be performed. A typical continuous processing machine of the type illustrated comprises a plurality of thread processing series each of which may produce a single multiple filament thread and includes a spinneret 95 together with its associated apparatus, reels 97 to 106, and coning device 107.

The machine as a whole may advantageously be arranged with a similar series of processing units extending longitudinally along either side of the center line of such a machine. The frame of the machine includes the vertical columns 108 and inclined beams 109 and 111. Upper and lower platforms 112 and 113, respectively, may be provided for the convenience of operators. Cross members 114 and 115, respectively, complete the frame. The base of the machine is

preferably enclosed as indicated by the casing 116. The gearing for the inclined bank of reels may likewise be enclosed by casing 117.

A suitable power source (not shown) at one end of the machine actuates a suitable speed-reducing device 118 which in turn rotates the horizontal cross shaft 119. Shaft 119 through the gears 120 and 121, respectively, drives the inclined shafts 122 on either side of the machine. These inclined shafts 122 are provided at intervals with take-off drives for the reels 98 to 106, inclusive, at various levels and the driving connections to the several reels include the gear boxes 128 and any suitable form of change speed mechanism comprising the gearing 123. Through suitable driving connections and the reduction gearing 124 the spin pumps supplying liquid viscose to the spinnerets for all of the several units are driven from the inclined shafts 122. In like manner power is transmitted from the inclined shafts 122 through the chain 125 and gearing 126 to the reels 97 supported upon the upper frame member 121.

The processing reels 98 to 105, inclusive, are supported from and driven by the gear boxes 128 actuated by the gearing 123, as previously explained. The several reels 98 to 106 driven by gear boxes 128 may be stopped by disengaging suitable clutch mechanisms operated by the lever 129. The liquid reagents are showered upon the thread as it traverses the reels by the distributors 131 supplied by the longitudinally extending conduits 132. The distributors 131 may be of any suitable type but preferably take the form of the device shown, described, and claimed in Patent No. 2,054,087, dated September 15, 1936, to Walter F. Knebusch et al. The liquid is then caught in the troughs 133 disposed below said reels and is carried away by suitable piping to be either discarded or recirculated, as may be desired.

The drying reel 106 may be of any suitable type, but is preferably tapered, as shown. The thread wound thereon may be dried by heating the elements of said reel by electrical means, live steam, hot water or hot air, the latter being used in the illustrated embodiment of the invention. Heated air is forced to the inner chamber of the drying reels from a suitable air heater through the ducts 134. Thread dried upon the tapered drying reel 106 is next passed through a suitable tensioning device 135 to the coning device 107. The coning device 107 is similar to that previously explained in the foregoing description of the other embodiments of the invention.

It should be noted that any of the various types of apparatus illustrated in the accompanying drawings may be modified to include any desired number of processing reels. Four such processing reels have been shown in certain of the foregoing embodiments. Many other changes in the methods and apparatus hereinbefore disclosed will occur to those skilled in the art; such changes may be made without departing from the spirit of the invention. It is intended that the patent shall cover, by suitable expression in the appended claims, whatever features of patentable novelty reside in the invention.

What is claimed is:

1. In the manufacture of multiple filament thread, the continuously performed steps of unwinding incompletely processed thread from a collecting package, meanwhile twisting the thread; subjecting the thread to one or more processing operations including at least one liq-

uid processing treatment while advancing the thread in a large number of generally helical turns along one or more thread-advancing thread store devices; drying the thread; and collecting the thread at a substantially constant linear speed in the form of a self-sustaining precision-wound cone package.

2. In the manufacture of spool-spun artificial silk thread or the like, the continuously performed steps of unwinding incompletely processed thread or the like from the spool on which it was collected during the spinning operation; subjecting the thread or the like to one or more processing operations including at least one liquid processing treatment while advancing the thread or the like in a large number of generally helical turns along one or more thread-advancing thread store devices; drying the thread or the like; and collecting the thread or the like at a substantially constant linear speed in the form of a self-sustaining precision-wound package.

3. In the manufacture of spool-spun artificial silk thread or the like, the continuously performed steps of unwinding incompletely processed thread or the like from the spool on which it was collected during the spinning operation, meanwhile twisting the thread or the like; subjecting the thread or the like to one or more processing operations including at least one liquid processing treatment while advancing the thread or the like in a large number of generally helical turns along one or more thread-advancing thread store devices; drying the thread or the like; and collecting the thread or the like at a substantially constant linear speed in the form of a self-sustaining precision-wound package.

4. In the manufacture of pot-spun artificial silk thread or the like, the continuously performed steps of unwinding incompletely processed thread or the like from the pot-spun cake in which it was collected during the spinning operation; subjecting the thread or the like to one or more processing operations including at least one liquid processing treatment while advancing the thread or the like in a large number of generally helical turns along one or more thread-advancing thread store devices; drying the thread or the like; and collecting the thread or the like at a substantially constant linear speed in the form of a self-sustaining precision-wound package.

5. In the manufacture of artificial silk thread or the like, the steps of extruding, coagulating, and, while it is still incompletely processed, packaging the thread or the like; unwinding the thread or the like from the package in which it is collected during the packaging operation, meanwhile twisting the thread or the like; subjecting the thread or the like to one or more processing operations including a liquid processing treatment while advancing it in a large number of generally helical turns along one or more thread-advancing thread store devices; drying the thread or the like; and collecting the thread or the like at a substantially constant linear speed in the form of a self-sustaining precision-wound package.

CHARLES E. HERRSTROM.

FRED. J. SAMERDYKE.

WALTER S. BARLOW.
